UNITED STATES PATENT OFFICE.

FRANCIS M. WILKINSON, OF BIRMINGHAM, ALABAMA.

WINDOW-SHADE FIXTURE.

SPECIFICATION forming part of Letters Patent No. 519,979, dated May 15, 1894.

Application filed August 26, 1893. Serial No. 484,111. (No model.)

To all whom it may concern:

Be it known that I, FRANCIS M. WILKINSON, of Birmingham, in the county of Jefferson and State of Alabama, have invented a new 5 and useful Improvement in Window-Shade Fixtures, of which the following is a specification.

My invention relates to that portion of a window shade fixture which serves to support 10 the shade roller. It is desirable to have a support for the shade roller that will be applicable to any length of roller or width of shade, since as a house is occupied successively by different tenants the window frames 15 are mutilated by the nails or screws used in putting up the ordinary brackets, and as the shade rollers of different tenants are rarely of the same length, the nail holes previously made present a very unsightly appearance.

20 My invention is designed to provide a permanent roller support which is put up once for all, and remains on the window frame, and is adjustable to receive any length of shade roller which may be used on such window.

25 It consists in a right angular bracket flat in cross section and having its longer shank portion arranged parallel to the roller and in horizontal position and provided with teeth 30 or notches on one of its edges, and its shorter section bent outwardly at right angles to the shank portion and provided with a bearing for the roller journals, in combination with a single staple or keeper arranged to straddle 35 the shank portion obliquely and be driven into the window frame to sustain the said shank portion in a horizontal position, as will be hereinafter more fully described with reference to the drawings, in which—

40 Figure 1 is a front elevation of a window frame and shade provided with my improved shade roller support. Fig. 2 is an enlarged front view of one of the supports; Fig. 3 a top or plan view of the same, and Fig. 4 a detail view of a modified form of the keeper.

45 In the drawings A represents the window frame, B is a shade, and C the shade roller which at its ends is provided with the usual journals or trunnions *a a*. The shade roller 50 support at each end is exactly alike, except

that to facilitate the insertion of the roller journals one bracket has a hole and the other a slot as usual. These brackets are made of flat metal bent at right angles so that the part D in which the journals rest, stands at 55 right angles to the window frame, while the shank portion D' lies flat against the window frame in a horizontal position and parallel with the roller. The lower edge of this shank portion is cut into a series of notches or teeth 60 *b* which constitutes at the same time a means for adjusting and locking the bracket in position. These brackets are held in elongated staples or keepers E which are driven into the window frame until the middle part of 65 the staple is just close enough to the window frame to allow the shank of the bracket to play freely through the same. These staples are made wider than the transverse dimensions of the shank of the bracket, so that the 70 staple may straddle the said shank of the bracket in an oblique position, and when in this position the bottom leg of the staple forms a fulcrum for the toothed edge of the shank, while the upper leg of the staple acts 75 as a lock to limit the downward movement of the outer end of the bracket, so as to hold it always in a horizontal position. When thus held the bracket is firmly locked against longitudinal movement by the engagement of its 80 teeth with the lower leg of the staple, and yet if it is desired to adjust the brackets to a longer or shorter shade roller, this may be quickly and easily accomplished by simply turning the shank of the bracket at right angles to the staple as shown in dotted lines 85 and slipping it farther in or out as the case may be, the teeth having plenty of room to pass through when in this position, owing to the fact that the staple is wider than the 90 transverse dimensions of the bracket shank.

As a modification of the staple, or in place of the same, a keeper consisting of a flat bar with two screws or nails may be used, as shown in Fig. 4.

Having thus described my invention, what I claim as new, and desire to secure by Letters Patent, is—

A shade roller support consisting of a right angular bracket having a long shank portion 100

D' with teeth or notches on one of its edges, the said shank portion being arranged parallel to the roller, and at the end of said shank portion a short section D at right angles to the shank portion provided with an opening or bearing for the roller journal, and a staple or keeper E made wider than the transverse dimensions of the shank portion and adapted

to straddle the same in a diagonal position to hold it horizontal substantially as and for the purpose described.

FRANCIS M. WILKINSON.
